UNITED STATES PATENT OFFICE.

PERCY C. CUNNINGHAM, OF LOS ANGELES, CALIFORNIA.

DESIGN FOR A FRONT FOR AN ELECTRICAL FLATIRON RECEPTACLE.

Application filed January 26, 1926. Serial No. 16,276. Term of patent 14 years.

To all whom it may concern:

Be it known that I, PERCY C. CUNNINGHAM, a citizen of the United States, residing at Los Angeles, in the county of Los Angeles and State of California, have invented a new, original, and ornamental Design for Front for an Electrical Flatiron Receptacle, of which the following is a specification, reference being had to the accompanying drawing, forming part thereof.

Figure 1 is a plan view of a front for an electrical flatiron receptacle, showing my new design.

Figure 2 is a front elevation of the front for an electrical flatiron receptacle.

I claim as my invention:

The ornamental design for a front for an electrical flatiron receptacle, as illustrated in the drawing.

Signed at Los Angeles, in the county of Los Angeles, State of California, this 18th day of December, 1925.

PERCY C. CUNNINGHAM.
